UNITED STATES PATENT OFFICE.

JOSÉ CORONEL, OF HABANA, CUBA.

AEROPLANE.

1,115,510.

Specification of Letters Patent.

Patented Nov. 3, 1914.

Application filed December 3, 1913. Serial No. 894,446.

To all whom it may concern:

Be it known that I, José CORONEL, a citizen of the Republic of Cuba, residing at Habana, Cuba, have invented certain new and useful Improvements in Aeroplanes, of which the following is a specification.

My invention appertains to a flying machine or aeroplane of novel and improved construction, the primary object of which resides in a machine of this character having supporting planes arranged and shaped similar to the wings of a bird and adapted to function in a manner similar to the wings, head and tail of a bird, whereby greater stability is obtained than is possible with the types of flying machines in present day use.

The construction hereinabove referred to enables the operator of the machine, constructed according to my invention, to navigate in the air in a manner similar to that of a bird, making large plane flights, swooping and alighting on the ground without making use of the motor power, such power only being used to rise from the ground.

In the drawings annexed hereto and forming a part of this specification, and in which I have illustrated one preferred embodiment of my invention:—Figure 1 is a top plan view of the aeroplane. Fig. 2 is a front elevation. Fig. 3 is a side elevation. Fig. 4 is a detail perspective view showing the relative arrangement of two of the supporting planes and connections therebetween, together with the operating lever. Fig. 5 is a detail perspective view showing the steering mechanism, and the gyroscopic planes of the tail, together with the actuating pedal.

Referring particularly to the drawing:—The central body 3 of the frame is provided with the oppositely extending frames 1 and 2 inclined toward each other at an angle of preferably 34° with respect to the horizontal. At the rear of the central body 3 of the frame is mounted the tail frame 4, preferably constructed in the form of a truncated pyramid of four sides, both the side frames and the central body frame being constructed with four sides of parallelepipedal form, said frames being strengthened by diagonally extending stay rods 5.

At the top of the central body 3 of the frame is provided a supplementary frame 6 which, besides carrying the steering rudder 38, serves to reinforce and support the frames 1 and 2. Also, at the bottom of the frames 1, 2 and 3 is provided a bottom sup-

plementary frame 7 to which are fixed the pontoons or buoyant members 8, also carried by the frame 7 is a frame 10 connected resiliently thereto by means of the spring 9, which serves to lessen the shock in alighting from a flight. The frame 10 also carries wheels 11 which enable the aeroplane to run over the ground.

Within the central body 3 of the frame is mounted a motor, said motor not being shown as it forms no part of this invention, but this motor is operatively connected to the propeller shaft 12, the propeller 13 being mounted on the shaft 12 and disposed in the front of the aeroplane. The operator's seat 14 is located within the central body 3 of the frame behind the said propeller 13 and beneath the shaft 12.

Carried by the inclined frames 1 and 2 and laterally disposed, are the supporting planes 15 and 16, one pair being mounted in each of the frames 1 and 2, and each of said pairs comprising an upper plane 15 and a lower plane 16, respectively, which have an undulated or bulging surface, the bulge lying substantially over the longitudinal axis thereof. Each of the same planes 15 and 16 is provided at the tip of their rear edges with a widened portion or fin 17. The said planes 15 and 16 of each pair are positioned parallel with respect to each other and mounted on pivots 18 journaled in the bearings 19 carried by the frames 1 and 2. Said planes 15 and 16 of each pair are also connected together by means of the cables 21 so that they may be moved in unison, their surfaces always remaining parallel. To the bottom plane 16 of each pair of supporting planes are secured cables 22 and 25 running in pulleys 23 and 26, respectively, and secured at the other end to the lever 24 mounted within reach of the operator, so that the said supporting planes 15 and 16 may be tilted as desired, the said pairs being operative independently of each other.

In the tail frame 4 are mounted the two planes 27 and 28 of fan-shaped or trapezoidal form. These planes are arranged parallel with each other and are also positioned one above the other, being connected together at their rear by uprights members 29, and swingingly mounted at their forward portions by means of the laterally disposed pivots 30 journaled on the frame 4. To the sides of the upper plane 27 and the lower plane 28 are connected the ends 31 and 32

2
of a cable which is guided by pulleys 33 and 34 mounted on the tail frame 4, and on the central body 3 of the frame. This cable is coiled around the cylindrical member 35 fixed on the vertical axle 36 mounted on the central frame 3 in front of the operator's seat, and provided with a hand wheel 37, whereby the said cylindrical member 35 may be rotated, thus moving the cable which operates to change the position of the said planes 27 and 28.

At the top of the central body 3 of the frame and in the top supplementary frame 6 is mounted the steering rudder 38, vertically disposed with respect to the horizontal, and revoluble about a pivot 39. At the front the rudder 38 is connected with the cables 40 and 41 which are guided over the pulleys 42 and 43, respectively, said pulleys being mounted on the frame 3. Said cables terminate by being connected to the central arm 44 which forms an integral part of the pedal member 45 journaled on the vertical axle 38, thus the said pedal 45 serves to operate, through the cables 40 and 41, the rudder 38.

The supporting planes 15 and 16 serve as elevating planes and are also used to ascend or descend according to the inclination given them by means of the lever 24, thus it will be seen that the usual elevating planes placed at the front of the machine are eliminated. Also, it will be seen that in the operation of the aeroplane, by moving the pedal 45, the steering rudder 38 may be moved one way or the other, to turn the aeroplane to the right or to the left. However, this movement to the right or left may also be accomplished by downwardly inclining the lateral planes 15 and 16 disposed on the side toward which it is desired to turn, and upwardly inclining the planes 15 and 16 of the other side.

The planes 27 and 28 are properly called stability planes, for besides sustaining the aeroplane when they are in the normal horizontal position, which is the position shown in full lines in Fig. 3, they prevent the aeroplane from capsizing longitudinally or turning over and over, this stability is attained by moving the planes 27 and 28 upward or downward by means of the handle 37.

In the operation of the machine constructed according to my invention, when the op-

erator becomes familiar with the handling 55 of the same, he will find that he will be able to maintain himself in the air for a long time without use of the motor, for he will simply have to take advantage of the currents of air, using them as a medium to gain 60 speed and to rise when he wishes.

It is to be understood that I do not limit myself to the particular construction and arrangement of parts herein set forth and described, but may resort to such modifications as fall within the scope of my claims.

I claim:

1. In an aeroplane and its complemental wings, the combination in each wing of a plurality of planes each provided with a 70 bulging portion disposed along the longitudinal axis, said planes in each wing being disposed parallel with respect to each other, and the planes of the respective wings being inclined in a transverse direction with respect to the longitudinal axis of the aeroplane, also the planes of one wing being inversely inclined with respect to the planes of the other wing, said planes being pivoted to rotate about their longitudinal axes, 75 means for connecting the planes of each wing together, whereby they may be moved in unison, hand levers for moving the planes of each wing, and means operatively connecting said hand lever and the planes of 80 each wing.

2. In an aeroplane and its complemental wings, the combination in each wing of a plurality of lateral gyratory planes inclined in a transverse direction with respect to the 90 longitudinal axis of the machine and the planes of one wing being inclined in an inverted way with respect to the planes of the other wings, a steering rudder mounted at the top of the aeroplane and disposed between the wings of the same, a plurality of tail planes pivoted at their forward edges and adapted to move in unison, and means for operating the lateral gyratory planes, steering rudder, and tail planes independently of each other.

In testimony whereof I have hereunto set my hand in presence of two subscribing witnesses.

JOSE CORONEL.
